HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

DOUBLE MULTICOLOR WEB PERFECTING ROTARY PRINTING PRESS

Application filed April 16, 1930. Serial No. 444,748.

This invention comprises a double multicolor web perfecting rotary printing press in which the printing units are located in the same longitudinal vertical plane but in different horizontal planes.

This invention further comprises a structure in which the plate cylinders of one printing unit are disposed around the upper side of their impression cylinder and the plate cylinders of the other printing unit are disposed around the lower side of their impression cylinder.

A practical embodiment of this invention is represented in the accompanying drawings, in which

Fig. 1 represents diagrammatically a top plan view of the press with the inking mechanisms removed; and

Fig. 2 represents diagrammatically a side elevation of the press.

In the first multicolor printing unit of the press the impression cylinder is denoted by 1 and its plate cylinders by 2, 3, 4, 5, which plate cylinders are shown as arranged around the upper side of the impression cylinder. These plate cylinders are provided with inking mechanisms 6, 7, 8, 9 of any well known or approved form.

In the second multicolor printing unit of the press the impression cylinder is denoted by 10 and its plate cylinders by 11, 12, 13, 14, which plate cylinders are arranged around the under side of the impression cylinder. These plate cylinders are provided with inking mechanisms 15, 16, 17, 18 of any well known or approved form.

The two multicolor printing units are arranged in the same longitudinal vertical plane but in different horizontal planes.

The web 19 to be printed in multicolor on both sides passes from its supply roll, not shown, over a roll 20 and under a roll 21 to and around the upper side of the impression cylinder 1 of the first printing unit under the plate cylinders 2, 3, 4, 5. From thence the web printed in multicolor on one side is fed under the roll 22 to and over a roll 23 and around the under side of the impression cylinder 10 of the second printing unit between said impression cylinder, and the plate

cylinders 11, 12, 13, 14. From thence the web printed in multicolor on both sides is led over a roll 24 to a cutting mechanism, such, for instance, as a pair of coacting rotary cutters 25, 26.

An offset web 27 is shown as being fed from its supply roll 28 to and around the impression cylinder 10 of the second printing unit and from thence to its take up roll 29.

The two printing units of the press may be driven from a common source of power, such, for instance as an electric motor 30 which is herein shown as having a pulley and belt drive connection 31, 32, 33 with a cross shaft 34 connected through a train of gears 35, 36, 37, 38 with the impression cylinder 1 of the first printing unit and through the bevel gears 39, 40, shaft 41, bevel gears 42, 43, shaft 44 and train of gears 45, 46, 47, 48 with the impression cylinder 10 of the second printing unit.

From the above description it will be seen that I have provided a structure in which the two printing units are arranged in the same longitudinal vertical plane but in different horizontal planes, the two units being so related as to facilitate the passage of the web therethrough with a minimum distance to travel.

It is evident that various changes may be resorted to in the construction, form and arrangement of the several parts without departing from the spirit and scope of my invention, and hence I do not intend to be limited to the particular embodiment herein shown and described, but

What I claim is:—

1. In a double four color web perfecting rotary printing press, first and second multicolor printing units arranged in the same longitudinal vertical plane but in different horizontal planes, each printing unit comprising an impression cylinder and four plate cylinders, the four plate cylinders of one printing unit being arranged around the upper side of their impression cylinder and the four plate cylinders of the other printing unit being arranged around the under side of their impression cylinder.

2. In a double four color web perfecting

rotary printing press first and second multi-color printing units arranged in the same longitudinal vertical plane but in different horizontal planes, each printing unit comprising an impression cylinder and four plate cylinders, the four plate cylinders of the first printing unit being arranged around the upper side of their impression cylinder and the four plate cylinders of the second printing unit being arranged around the under side of their impression cylinder.

3. In a double four color web perfecting rotary printing press, first and second multi-color printing units, each comprising an impression cylinder and four plate cylinders, the four plate cylinders of one printing unit being arranged around the upper side of their impression cylinder and the four plate cylinders of the other printing unit being arranged around the under side of their other impression cylinder.

4. In a double four color web perfecting rotary printing press, first and second multi-color printing units, each comprising an impression cylinder and four plate cylinders, the four plate cylinders of the first printing unit being arranged around the upper side of their impression cylinder and the four plate cylinders of the second printing unit being arranged around the under side of their impression cylinder.

In testimony that I claim the foregoing as my invention, I have signed my name this 11th day of April, 1930.

35 HOWARD M. BARBER.
